COLLAPSIBLE PICNIC TABLE AND BENCH ASSEMBLY

Robert E. Hagan, Youngstown, Ohio

Application August 4, 1950, Serial No. 177,733

6 Claims. (Cl. 155—123)

1

This invention relates to portable picnic equipment and more particularly to a combined bench and table of the type generally used for picnics, outdoor parties and the like.

The primary object of this invention is to provide a bench and table combination for use as above mentioned which is light in weight and of such construction as to be collapsible to the degree that it may be easily carried and readily stored in a small space.

Another object of my invention is the provision of a portable and collapsible table and bench combination which is so constructed as to allow seats integrally extending therefrom to be folded within the peripheral limits of the table top.

A further object of my invention is the provision of a collapsible picnic table and bench assembly constructed of materials such as wood, pipe and tubing to effect a desired economy in construction and to provide the lightness of weight necessary for good portability. It has been found that for small sizes the outside diameter of standard tubing is substantially equal to the inside diameter of standard pipe of the same nominal dimension. This fact is used to good advantage in the construction of my invention as will be hereinafter explained.

Other objects and advantages of my invention will become apparent upon consideration of the following detailed specification and accompanying drawing wherein there is disclosed a certain preferred embodiment of my invention.

In the drawing:

Figure 1 is a perspective view of a table and bench assembly constructed according to the principles of my invention, showing the table assembled and ready for use;

Figure 2 is a side elevation of the table and bench assembly of Figure 1;

Figure 3 is a perspective view of the assembly of Figure 1 but showing one of the seats folded underneath the top to provide more convenient access to one side of the table;

Figure 4 is a perspective view of the assembly of Figure 1 showing the same collapsed and packed for storage; and

Figure 5 is a fragmentary sectional view of one of the joints between a leg member and a frame member of the assembly of Figure 1.

In the embodiment of my invention shown in the various figures of the drawing the table and bench assembly comprises in combination a top 10, seats 11, legs 12, and a frame member 13.

The table top 10 is preferably formed of several flat boards 17 laid side to side to form a flat

rectangular surface. An angle iron 14 or other suitable rigid member is positioned transversely under said boards 17 near each end, and secured thereto by screws, not shown, or equivalent means. A short length of standard pipe 15 is affixed near each end of each of said angles 14, said pipes 15 depending vertically to form sockets to receive legs 12 to be hereinafter more fully described. A wing nut 16 or other suitable device is positioned in said pipe 15 to provide means for securing said leg 12 when inserted therein.

Each of the seats 11 consists of a flat board 18, which is wide enough to provide reasonable comfort for a person seated thereon, and approximately the same length as the boards 17 of the top section 10. A stud 18', formed of a short length of standard metal tubing, projects downwardly from the board 18 near each end thereof. Flanges are formed in or secured to the studs 18' at their upper ends, as is shown, for the attachment of the studs to the boards 18.

In the embodiment shown I have provided four leg members 12 arranged in pairs. Each of said leg members 12 consists of a J-shaped length of standard metal tubing. Secured at its upper end by the socket 15 is the longer vertical section 19 of said leg member 12. The shorter vertical section 21 is positioned outwardly of said section 19 and is connected integrally therewith by means of a horizontally disposed section 20. Said section 21 is turned inwardly at 22 and a vertical socket 23 of standard pipe is secured at its inner extremity to slidably engage the stud 18' depending from the board 18. A wing nut 24 is provided in said socket 23 as means for retaining said stud 18' in engagement therewith.

Engaging the legs 12 at their lower end is the frame member 13 which has as its principal element an elongated section of standard tubing 25, said section 25 being of sufficient length to span the distance between the pairs of leg sections 12. A short section of tubing 27 is secured normally to section 25 at each end thereof, and a short length of standard pipe 28 is secured in vertically disposed fashion to each end of each of said sections 21. As assembled, the four pipe sections 28 are substantially parallel and are disposed normally to the plane formed by the tubing sections 25 and 27. An annular collar 26 is positioned on the lower portion of the longer vertical section 19 of the leg member 12 and is secured thereto as means for supporting the frame member 13.

To assemble my unit, section 19 of each leg member 12 is inserted into a pipe section 28 of

the frame 13, said frame being retained at the proper height by the annular collars 26. The pipe sections 15 depending from the table top 10 are engaged with the tops of sections 19 of the legs 12, and the studs 18 depending from the seats 11 are inserted into the pipe sections 23. The seats are then swung into the position desired and the wing nuts 16 and 24 are firmly tightened to render the assembly a rigid unit.

For storage and moving, the wing nuts 16 are loosened to permit top 10 to be lifted from the supporting sections 19. Wing nuts 24 are then loosened to permit the removal of the seats 11.

The top and seats are then rested edgewise on sections 27 of the frame 13. The legs 12 are then folded inwardly against said top and seats as is shown in Figure 4. The unit is then flat and compact for easy moving and storage.

Particular attention should be paid to the fact that when the assembly is collapsed the studs 18 of the seats 11 may be inserted into the pipe section 15 of the top 10. This will assure that the seats 11 are positively positioned and secured to guard against damage in transit.

It should be apparent upon full consideration of the description hereinbefore set forth that the advantages of my invention are manifold. Generally a portable table assembly of this type consists of benches, top, and some form of collapsible legs upon which the top is supported. This particular arrangement, while fulfilling the general requirements for portability, is usually heavy and cumbersome and must be carried piece by piece when moved. Furthermore, the storage space required is considerable since the benches normally are not collapsible. These objectionable qualities have been to a great extent eliminated in my invention. Metal tubing, of which a large portion of my table is constructed, is noted for its high strength-weight ratio. Assembly or disassembly requires but a few minutes time and the table assembly may be carried as a unit in either condition.

A further advantage of the table assembly constructed according to the principles of my invention is that either or both seats may be bolted within the peripheral limits of the top, thus facilitating any operation on or about the table which may be necessary or desirable before the seats are to be utilized.

In view of the preceding disclosure I claim:

1. A collapsible table assembly comprising in combination a pair of seats, a top consisting of flat boards laid side to side to form a substantially rectangular flat surface, said boards being held in flat relation by means of members disposed transversely thereunder and secured firmly thereto near each end thereof, said members having vertically disposed pipe sections secured thereto and depending downwardly therefrom, means on each of said pipe sections to detachably retain an end portion of a tube length, a plurality of legs each comprising a bent tubular member having a horizontally disposed section forming a base, vertically disposed sections extending upwardly from each end of said horizontal sections to form supporting elements for said top and seats, one of said vertical sections of each leg having an annular ring secured thereto near its lower end, and the other vertical section of each leg having a horizontally disposed section extending inwardly from its upper end, said inwardly extending section having a vertically disposed socket secured to its inner end, said socket having means positioned there-

on to detachably secure a tube inserted therein, a bracing assembly comprising a horizontally disposed longitudinal member having a horizontally disposed transverse member secured at each end thereof, each end of each of said transverse members having a sleeve secured in a vertically disposed position to slidably receive the vertical table-supporting sections of the aforementioned legs; and each of said seats comprising a wide flat board having a downwardly depending stud secured to the under side thereof near each end, said stud being adapted to fit slidably into the sockets secured to the aforementioned legs.

2. A collapsible table assembly comprising in combination a substantially rectangular flat top having vertically disposed and downwardly depending tubular sections secured thereunder near each end thereof; a plurality of supporting legs each having a horizontal section with a vertically disposed supporting section extending upwardly from each end thereof, one of said vertical sections of each leg having a projection positioned near its lower end, the other vertically disposed section of each leg having a horizontally disposed section extending inwardly from its upper extremity, and inwardly disposed section having a vertically disposed tubular section positioned thereon, and said legs slidably engaging said first mentioned tubular sections, a rigid bracing assembly of tubular construction slidably fitted over said legs to retain the same in horizontally spaced relation, said bracing assembly being supported by the aforementioned projections in said legs, and a pair of seats each having an elongated flat surface with vertically disposed and downwardly depending tubular sections secured thereunder to slidably engage said second mentioned tubular sections.

3. A collapsible table and bench assembly comprising in combination a tape top, a pair of transversely spaced sockets secured to and depending downwardly from said table top at each longitudinal end thereof, an elongated seat member for each side of the table having a pair of studs secured to and depending downwardly therefrom in spaced relation equal to the longitudinal spacing of said sockets, spaced pairs of J-shaped tubular frame members each having the upper end portion of its longer vertical reach positioned in one of said sockets, a vertically disposed socket at the upper end of each of the shorter vertical reaches of said J-shaped members to receive one of said studs, and means to retain the lower end portions of said longer vertical reaches of said J-shaped members in predetermined spaced relation, the arrangement being such that said J-shaped members may be swung inwardly about the axes of said longer reaches.

4. An assembly according to claim 1 further including releasable means on each of said sockets to restrain axial and rotational movement of said reaches relative to said sockets.

5. A collapsible table and bench assembly comprising in combination a table top and a bench member for each of two opposite sides of the table top, a pair of transversely spaced leg members adjacent each longitudinal end of said table top and each leg of each pair comprising a length of tubing bent to provide transversely spaced and upwardly extending reaches to support the table top and a bench member respectively, a bracing assembly rotatably receiving the lower end portions of each of said reaches supporting said table top, and means swivably interconnecting the upper ends of said reaches and said table top and

bench members whereby said leg members may be rotated inwardly about the vertical axes of the reaches thereof which support the table top.

6. Apparatus according to claim 5 further characterized in that said table top and said bench members are removable vertically from said leg members and in that the vertical reaches of said leg members which support said table top are sufficiently spaced to accommodate the removed table top and bench members in vertical edgewise position while supported on said bracing assembly.
